(57) **CLAIM**
The ornamental design for an ice screw, as shown and described.

(30) **Foreign Application Priority Data**

DESCRIPTION

Oct. 15, 2012 (EP) 002118653-0001

FIG. 1 is a perspective view of an ice screw;

(51) **LOC (10) Cl.** **08-05**

FIG. 2 is a front view thereof;

(52) **U.S. Cl.**

FIG. 3 is a top view thereof;

USPC **D8/387**

FIG. 4 is a right-side view thereof;

(58) **Field of Classification Search**

FIG. 5 is a left-side view thereof;

USPC D8/14, 382, 387; 248/231.9, 231.91;
411/400, 409, 402, 411; 7/145

FIG. 6 is bottom view thereof;

See application file for complete search history.

FIG. 7 is a rear view thereof;

(56) **References Cited**

FIG. 8 is a perspective view of the ice screw of FIG. 1, in

U.S. PATENT DOCUMENTS

which the arm portion is shown in the folded position;

5,118,061 A * 6/1992 Byrne et al. 248/231.9
5,782,442 A * 7/1998 Kwak et al. 248/231.9
6,068,226 A * 5/2000 Anders 248/231.91
6,505,799 B1 * 1/2003 Bercaw et al. 248/231.9

FIG. 9 is a front view thereof;

FIG. 10 is a top view thereof;

FIG. 11 is a right-side view thereof;

FIG. 12 is a left-side view thereof;

FIG. 13 is a bottom view thereof; and,

FIG. 14 is a rear view thereof.

The broken lines depict portions of the ice screw in which the design is embodied that are not considered part of the claimed design.
